METHOD OF PACKING CHAIRS FOR
SHIPMENTLouis W. Wekosin, Oshkosh, Wis., assignor to
Freeman Furniture Factories, Inc., Chicago,
Ill., a corporation of Illinois

Application September 24, 1938, Serial No. 231,500

2 Claims. (Cl. 45—22)

This invention relates generally to a novel and improved method for packing articles of furniture, and more particularly for packing chairs for shipping and storing purposes, whereby the 5 same will be more fully protected against damage or injury while in transit or in storage. Heretofore, chairs have been packed for shipping by individually covering as much of the chair as is possible by means of some suitable covering 10 material, such, for example, as excelsior, straw, or the like. This method of shipping was costly, because of the cost of materials and labor involved, and at the same time, such method of shipping was not adequate protection for rough 15 handling to which furniture is subject in transit.

Wrapping and packing the chairs individually also made it difficult to pile or stack the same in any great number, or in any compact manner, due to the fact that the backs and joints were 20 subjected to undue stress when the chairs were piled upon their sides.

It is well known that chairs are built to receive relatively great loads when standing upright, but when individually wrapped, as has heretofore 25 been done, the peculiar shape of the package resulting from such packing or wrapping, made it almost impossible to pack the chairs so that they remained in an upright position.

The main object of the invention is to provide 30 a novel and improved method of packing chairs for shipping and storage purposes, whereby the same will be capable of arrangement for neat and compact piling, with the chairs in a substantially upright position.

Another object of this invention is to provide 35 a novel and improved method of packing chairs for storage or shipping, whereby, although a substantial portion of the bare finish of the chairs packed is exposed, it is nevertheless fully protected against scratching or marring of the same.

A further object of this invention is to provide 40 a novel and improved means for packing chairs for shipment or storage, said means including only a few simple parts, readily assembled in 45 position around the chairs to be packed with a minimum of labor and at a greatly reduced cost of materials.

With the foregoing and other objects in view, which will appear as the description proceeds, the invention consists in certain novel features 50 of construction, arrangement and combination of parts hereinafter fully described, illustrated in the accompanying drawing, and particularly pointed out in the appended claims, it being understood that various changes in the form, proportion, size and minor details of the structure may be made without departing from the spirit or sacrificing any of the advantages of the 55 invention.

For the purpose of facilitating an understand-

ing of my invention, I have illustrated in the accompanying drawing, a preferred embodiment thereof, from an inspection of which, when considered in connection with the following description, my invention, its mode of construction, assembly and operation, and many of its advantages should be readily understood and appreciated. 5

Referring to the drawing in which the same characters of reference are employed to indicate 10 corresponding or similar parts throughout the several figures of the drawing:

Fig. 1 is a perspective view of a pair of chairs packed for shipping or storage by means of my new improved method; 15

Fig. 2 is a perspective view of the developed side of one of the elements employed with my method.

Referring to the drawing more specifically by characters of reference, the reference characters 20 A and B designate generally chairs of conventional construction, each comprising a seat 1, a back rest 2, the legs 3, and the brace structure 4. As the specific construction of the chair forms no basis of the present invention, it is not believed 25 necessary to describe the same in more detail.

In employing my improved method for packing chairs, the same are packed in pairs or multiples of two and are arranged, as shown in Fig. 1 of the drawing, with the chair A disposed 30 in an upright standing position, and the chair B arranged in an inverted position and placed with its seat against the seat of the chair A, said seat portions being spaced from each other and protected by some suitable strip of protective 35 material 10, such, for example, as corrugated board or the like, interposed between the two seats of said chairs for the protection of the finishes of said seats.

When in this position, it will be noted that the 40 forward portion of the seat of the chair B will be disposed adjacent the lower portion of the back rest 2 of the chair A, said portions being spaced from each other by means of a strip of protective material 11, so that it will be impossible 45 for said portions to come in contact with each other and thereby mar their finishes. Similarly, the forward portion of the seat of the chair A will be spaced by a strip of protective material, not shown, from the lower portion of the back 50 rest 2 of the chair B.

The chairs A and B are bound together in the above-described position by suitable wire elements 12 or some other means, which elements extend around the seats of said chairs securely 55 fastening said seats to each other, said wire elements or other binding means 12 being protectively held away from the side edges of the seat portions of said chairs by slabs or strips 13 of suitable protective material of paste board or 60

corrugated board disposed around said edges, thereby preventing said binding elements 12 from contacting said seat edges and cutting or marring the same.

5 The legs and back rests of the chairs A and B thus secured to each other are protected by suitable sheets of protective material, such as cardboard, corrugated board, or other similar material generally designated by the reference character 14, and one of which is shown developed in Fig. 2 of the drawing. Each of said sheets is of substantially rectangular formation and has its opposite edges folded and creased to produce the side flanges 15, which flanges are cut along their lengths at similarly placed opposite points, as shown at 16, 17, 18 and 19, so that the said sheet may be folded along the transversely disposed creases 20, 21, 22 and 23 to form the segments 24, 25, 26, 27 and 28 for a purpose to be presently more fully described.

10 In arranging the sheets 14 around the chairs A and B the portion 26 is disposed against the back of one of the chairs, said portion 26 being of such a size as to completely cover the back of 15 said chair, as shown in Fig. 1, so as to fully protect the upright or back rest 2 as well as the legs 3 thereof by partially encasing the same in the following manner.

15 As viewed in Fig. 1 of the drawing, the right-hand sheet 14 will be disposed, so that the segment 27 together with its associated segment 28 will form a pocket for enclosing the free ends of 20 the rear legs 3 of the chair B with the sheet 14 secured thereto by means of the wire binding element 29, the flanges 15 protecting the legs of said chair from becoming scratched or marred by the binding element 29. The lower portion of said right-hand sheet is folded so as to receive the 25 upper portion of the back rest 2 of the chair B, and the lower portion of the front legs of the 30 chair A, there being a sort of a hood formed by the segments 24 and 25 in cooperation with the large segment 26. The sheet is secured in this 35 folded position by means of the wire binding element 30. The flanges 15 in this case similarly protect the chairs from becoming marred or scratched by said wire element 30.

40 In a similar manner the left-hand sheet 14 is secured around the chairs A and B, but in this 45 case the wider segment 25 is arranged on top so as to encase the upper portion of the back rest 2 of the chair A and the lower portions of the 50 front legs of the chair B. The wire binding element 31 is employed for securing said sheet in its 55 folded position around said chairs. The lower portion of the left-hand sheet is folded so as to encase the lower portions of the rear legs of the 60 chair A and wire binding element 32 is employed for securing said lower portion of the sheet to the chair.

65 From the above, it will be noted that by reason of the strips 11, as well as the tying means 12, movement of the chairs A and B relative to each other when once packed and assembled with each other will be practically impossible, thereby 70 preventing injury to the finish of said chairs, which may be due to frictional contact between the same were the same capable of movement relative to each other.

75 It will also be noted that although the major portion of the bare finish of the chairs is ex-

posed the same is nevertheless adequately protected against injury as it is quite impossible for any portion of the bare finish of one package to come in contact with the exposed surface of the next adjacent package.

80 It will also be noted that to complete satisfactory packing of the chairs requires only the sheets 14, which are of identical size and construction, which may be readily stacked in place in large quantities without occupying too great space. It 85 will also be noted that only a few simple tying operations are required to complete the package, and when so completed, the chairs may be arranged in an upright position and in a compact manner.

90 It will also be noted that the means and method hereinabove described will readily lend itself to pack for shipping and storage purposes chairs in multiples of two by merely increasing the width of the sheet 14 to include the required number of 95 pairs of chairs, and if desired, placing walls of protective material between each pair so packed.

100 It is believed that my invention, its mode of construction and assembly, and many of its advantages should be readily understood from the foregoing without further description, and it should also be manifest that while a preferred embodiment of the invention has been shown and described for illustrative purposes, the structural details are nevertheless capable of wide variation 105 within the purview of my invention as defined in the appended claims.

110 I claim:

1. A package for shipment of chairs, comprising means protectively binding a pair of chairs together with their seats facing each other and disposed one on top of the other, and a pair of sheets of relatively stiff protective material secured to said chairs, each of said sheets extending the full length of the package and including a 115 hood for enclosing the upper portion of the back rest of one chair and the lower portions of the forward legs of the other chair, and a second hood disposed at the other end thereof for enclosing the lower portions of the back legs of said first 120 chair, said hoods being formed integral with and bent from their respective sheets, said sheets having flanges formed integral therewith and extending inwardly for protecting the uncovered sides of said package.

125 2. A package for shipment of chairs, comprising means protectively binding a pair of chairs together with their seats facing each other and disposed one on top of the other, and a pair of sheets of relatively stiff protective material secured to said chairs, each of said sheets extending the full length of the package and including a 130 hood for enclosing the upper portion of the back rest of one chair and the lower portions of the forward legs of the other chair, and a second hood disposed at the other end thereof for enclosing the lower portions of the back legs of said first chair, said hood being formed integral with and bent from their respective sheets, said sheets having flanges formed integral therewith and extending inwardly for protecting the uncovered sides of said package, said inwardly extending flanges being maintained in a substantially perpendicular relationship to said sheets by said binding means.

135 LOUIS W. WOKOSIN.
